SCRUBBING BRUSH OPERATED BY WATER POWER

Max Jack Demo, West Los Angeles, and Cloyd D.
Smith, Pacific Palisades, Calif.

Application January 23, 1950, Serial No. 140,078

7 Claims. (Cl. 15—29)

1

This invention relates to scrubbing brushes operated by water power, and more particularly to a hand brush which can be held in the hand of the user and manipulated for washing automobiles and other purposes, and where the water which drives the rotatable brush is directed to the brush as the cleaning fluid used therewith.

Among the salient objects of the invention are: To provide a scrubbing brush of the character referred to in which the handle not only has the water passageway therethrough, but in which, around said water passageway, is a soap container for liquid soap, with means easily operated by the hand or thumb of the user, to admit soap into the stream of water passing through the handle to the brush; to provide in a brush of the character referred to an improved rotor in the top part of the body of the brush, with means for directing the water against said rotor for driving it, with a train of gears therefrom, in a chamber below said rotor chamber, for driving a rotatable scrubbing brush supported in the lower, open bottom of said brush body; to provide means for detachably connecting the scrub brush in operating position to the drive member, whereby it can be easily disconnected for cleaning, repair or to be interchanged for another brush.

Other objects and advantages will appear from the following more detailed description of one practical embodiment thereof, taken with the accompanying sheet of drawings, in which:

Figure 1 is a plan view or elevation of a scrubbing brush embodying my invention;

Figure 2 is a vertical sectional view through the brush body and a part of the handle, to show the interior construction and arrangement;

Figure 3 is a fragmentary view of the handle, partly in section;

Figure 4 is a sectional view taken on line 4—4, Fig. 2;

Figure 5 is a plan view of the member on top of the brush;

Figure 6 is a sectional view, on line 6—6 of Fig. 2;

Figure 7 is a cross sectional view on line 7—7, Fig. 3; and

Figure 8 is a partial bottom plan view of the rotor.

Referring in detail to the drawings, the body casting is designated 10, and is cup shape, with a dome-like top, and from one side of which extends a handle casting 11, having a central water passageway, designated 12 and around which, longitudinally of said handle casting is a circular, in cross section, soap chamber 13, seen in the sectional view in Fig. 6. From said soap chamber 13 is a small passageway 14 drilled in the casting 11, through which soap can be passed into the body, again referred to. This is controlled by means of a spring-loaded valve member 15, having a reduced, or neck portion 15' with a rubber gasket 16 around the extension 17 provided with a push cap or head 18, working in a guide

2

socket, as 19 formed on the side of the casting 11. When said valve member 15 is pressed inwardly, soap from the soap chamber 13 can flow through the small passageway 14 into the body, into which 5 water is discharged, from the water passageway 12, through the angular port 20, seen in light broken lines in Fig. 1, whereby to strike the rotor 21, between its angularly positioned vanes 21', 21'', as seen in Fig. 8, for driving said rotor. Said 10 rotor has a central shaft 22, having a bearing through an upwardly arched cross member 23, said shaft turning in a bushing 23' and having a small gear 24 on its lower end, as clearly seen in Fig. 2. Said small gear 24 is in mesh with a larger 15 gear 25, having a combination hub and gear, as at 26, on a pin or short shaft 27, the upper end of which is seated in the arched cross member 23, and its lower end is seated in another straight cross member 28 secured by screws to the body casting, said member 28 having an upturned flange portion 29 which fits in a channel, at each 20 end, formed on the inner face of the body casting and designated 30, said flange portions bearing against the upper member 23 and supporting it 25 in place, as will be understood from the sectional view, Fig. 2, and indicated in broken lines, Fig. 4. There is an upturned flange portion 29 at each end of said member 28.

Mounted in said cross member 28 is a bushing 31, through which a shaft 32 extends from a gear 33 on top of said cross member 28, as shown, said gear being in mesh with the small gear portion 26, formed as a part of the large gear 25, as seen in Fig. 2. Secured to the lower end of said 35 shaft 32 is a central hub portion 34, made as a part of a disc or member 35, of wheel-like form, with openings 36 therein, designated in Fig. 4 with the neck extensions as parts of said openings, and well known as an attaching and detaching means.

A round brush body, designated 37, with the bristles 38, is shown as having a top plate or disc 39, seen in plan view in Fig. 5, with the large headed pins 40, secured therethrough and anchored in the body of the brush, as seen at 41, Fig. 2, said body being of rubber, or similar material, and the ends of said pins being permanently seated therein. Said pins have an intermediate part, next to the head, designated 42, and adapted to be turned into the neck portions 45 of said openings 36, as will be understood from the showing in Figs. 2 and 4. In this manner the brush can be attached and detached from the top plate member 35. The heads of the pins will pass through the large parts of said openings 36, and when turned, the heads ride on top of said plate member 35, as indicated in Fig. 4. Thus by a partial turn of said brush body, the heads of the pins will register with the large parts of said openings 36, and said brush can be pulled straight out, for cleaning, repair or change.

Connected with the tubular extension 11 from the body 10 is a cylindrical or tubular handle

portion 43, which also forms the extension of the soap chamber, as at 13', and of the water passageway, as 12', said soap chamber communicating with the small bore 14 for conveying soap from the soap chamber into the body, as will be understood from Fig. 2. Said handle portion 43 is covered with suitable material, as rubber, designated 43', and at its outer end said handle is tapered and provided with a threaded end 44, for connecting a water hose 45 thereto, as indicated. The water passageway inner tubular member 12' is provided on its wall with a valve element 46, having a slit 47 in its end, whereby water from said passageway 12' can be discharged in small amount into the soap chamber 13', as will be understood from Figs. 3 and 7. A screw closure member 48 is shown in place for closing an opening through which soap is supplied to the soap chamber 13', clearly indicated in Figs. 1 and 3.

In the side of the handle casting 11, we have also shown a removable plug 50, also indicated in Fig. 1, to give access into the member 11 and to the small discharge port 20 into the rotor chamber, and through which said angular port 20 can be drilled, as will be seen from Fig. 1.

Around the body 10 of said machine is a rubber or other soft shield or bumper, shaded to indicate that it is made of rubber, and designated 49 at the lower right hand corner of Fig. 2.

We are aware that changes in the details of construction and arrangement can be made within the scope of the invention, and we do not, therefore, limit the invention to these details as shown for purposes of description and explanation, except as we may be limited by the hereto appended claims.

We claim:

1. A water powered cleaning brush including an inverted cup-like body, open on its bottom and having connected at one side between the top and bottom thereof a combination inflow tube for water and a handle, with a discharge port into the top of said body, a cup-like rotor in the top of said body, opposite said discharge port, whereby water discharged through said port drives said rotor, an arched supporting member in said body, under said rotor, with a bearing portion extended up under said cup-like rotor, a shaft from the center of said rotor through said bearing portion, a pinion on the end of said shaft, a second supporting member in said body below said first supporting member, a large gear mounted on said second supporting member and having a shaft therefrom through said second supporting member, a cleaning brush mounted in the open bottom of said body, under said second supporting member, and connected with the shaft from said large gear, a large gear in mesh with the pinion on the rotor shaft, said large gear having a pinion portion in mesh with the large gear mounted on said second supporting member, whereby to drive said brush from said rotor, and a soap chamber formed in said handle, with a valve controlled inlet therefrom to the said body, said valve being operable manually at will to admit soap to said body.

2. A claim as set forth in claim 1 in which the soap chamber is of annular form in cross section around said inflow tube for water in said handle.

3. A claim as set forth in claim 1 in which the inflow tube for water is provided with a valve element with an opening therein to permit a small amount of water to be discharged into said soap chamber.

4. A water power brush including an inverted cup-like body with a combination handle and water supply tube connected into one side of said body, with a discharge port into said body, 5 an inverted cup-like rotor rotatably supported in the top of said body, opposite said port, to be driven by water discharged through said port, a cleaning brush mounted in the open side of said cup-like body with its bristles extended 10 downwardly therefrom, two supporting members across the inside of said body, one above the other, one supporting said rotor above it and the other supporting said brush below it, a gear train from the rotor to said brush, between said supporting members in said body, and a soap chamber formed in said handle with a valve controlled small passageway therefrom into said body, said valve being manually operable at will to admit soap to said body, to mix with the 15 water therein.

5. A claim as set forth in claim 4, in which the soap chamber is formed around the water supply tube in said handle.

6. A claim as set forth in claim 5, in which 25 said water supply tube, within the soap chamber around the outside thereof, has a small leak valve in its side to permit water from said water supply tube to be discharged in small amount into said soap chamber.

7. A scrubbing brush to be operated by water power and including a body of inverted cup-like form, a handle extended from one side thereof, said handle having a water passageway there-through, and a separate soap chamber therein 30 around said water passageway, an arched support across the inside of said body, a rotor mounted over and upon said arched support and having a power shaft extending therefrom through said arched support, said rotor having vanes around its periphery for driving said rotor, a pinion on the lower end of said power shaft, a second supporting member across the inside of said body below said arched support, a gear flatwise upon said second supporting member 35 and having a drive shaft therethrough, an intermediate gear between said arched support and said second supporting member, at one side of the center of said body, said intermediate gear being in mesh with the pinion on said power shaft, to be driven thereby, said intermediate gear having a combination hub and pinion in mesh with the gear flatwise on said second support for driving the latter gear, a scrubbing brush detachably connected with the lower end 40 of said drive shaft, in the lower open side of said body, said handle having an inlet port from said water passageway to said rotor for driving the latter, and a valve-controlled passageway from said soap chamber into said body for soap 45 to mix with the water therein.
